LOOM HARNESS

Frank H. Kaufmann, Huntingdon Valley, Pa., assignor to Steel Heddle Manufacturing Company, Philadelphia, Pa., a corporation of Pennsylvania

Application June 21, 1950, Serial No. 169,493

9 Claims. (Cl. 139—92)

1

This invention relates to loom harness, and it relates more particularly to the construction and arrangement of the frames, and the parts carried thereby, used for supporting the heddles which separate the warp ends into successive sheds for the passage of the shuttle therebetween to effect the weaving operation.

Heretofore most of the frames, used in looms for supporting the heddles, were made with top and bottom rails or shafts of wood, connected at their ends by side struts, usually made of metal strips secured to the ends of the top and bottom rails or shafts.

By reason of the present availability of light metal alloys of aluminum or magnesium, it has been suggested to substitute, for the top and bottom rails made of wood, rails or shafts made of light metal alloys which are extruded through dies in the desired shape in cross-section, the same preferably being made hollow for economy of metal and diminution of weight.

However, the metal of which said rails or shafts are made is relatively soft, and certain difficulties have arisen in the use of such metallic rails or shafts, principally in connection with the means for supporting the heddle rods in the frames intermediate the ends thereof.

It has also been suggested to provide rails or shafts, in which the main or body portion is made of wood, having metallic parts mounted on one or both edges thereof, which may also be made of extruded metal alloys, but here again similar difficulties have arisen.

The principal object of the present invention is to provide a novel and efficient form of heddle frame in which the top and bottom rails or shafts may be made wholly or in part of extruded metal shapes, which frame is so constructed and arranged, and the parts thereof so shaped, as to provide improved means for supporting the heddle rods intermediate the ends thereof.

A further object of the present invention is to provide, in a heddle frame of the character aforesaid, improved means for supporting the heddle rods intermediate their ends, which will permit the use of slide hooks of usual, ordinary, and accepted types, whereby the heddles may be supported on the rods in such manner as to be permitted a sufficient sidewise displacement in the frame whenever necessary for the prevention of warp streaks in the cloth being woven.

The nature and characteristic features of the present invention will be readily understood from the following description, taken in connec-

2

tion with the accompanying drawing, forming part hereof, in which:

Figure 1 is a front elevation of a loom harness frame embodying the main features of the present invention;

Fig. 2 is a fragmentary view, enlarged, of a portion of the structure shown in Fig. 1;

Fig. 3 is a transverse section, further enlarged, taken on the line 3—3 of Fig. 2;

Fig. 4 is a view similar to Fig. 3, the section, however, being taken on the line 4—4 of Fig. 2; and

Fig. 5 is a sectional view, similar to Fig. 3, illustrating a modified form of the invention in which the main or body portion of the rail is made of wood, having mounted on its inner edge a metallic member for utilizing the features of the present invention.

It should, of course, be understood that the description and drawing herein are illustrative merely, and that various modifications and changes may be made in the structure disclosed without departing from the spirit of the invention.

Referring now more particularly to Figs. 1 to 4 of the drawing, the top and bottom rails or shafts 10 of the frame are connected at their ends by means of side struts 11. In this instance the side struts 11 may be, and preferably are, made of wood, whereas the top and bottom rails or shafts 10 are made of extruded metal shapes, preferably hollow, whereby they are provided with relatively thin side walls 12, and outer marginal portions 13, somewhat thicker than the sidewalls 12.

The outer marginal portion 13 of each of the top and bottom rails 10 is provided with a V-shaped groove 14, extending from end to end of the rail 10, exteriorly disposed, so that there is thus provided a drill point guide for drilling through the portion 13 at any required location in the length thereof wherever it may be desired to mount a hook 15 for connecting the actuating cord or straps (not shown), which are used for raising and lowering the frames in the loom in the usual and customary manner.

Extending inwardly from the inner marginal portion of each rail or shaft 10, toward the center of the frame, is a longitudinal hollow rib 16, the overall thickness of which is preferably somewhat less than that of the main or body portion of the rail 10.

The rib 16 being made hollow, has a portion of the interior thereof shaped as at 17 complementary to, and for the purpose of receiving, a

metal rod 18 which extends from end to end in the frame, and the remaining portion of the rib 16 is also preferably made hollow as at 19 for the purpose of lightening the structure.

At each of the locations where it is desired to mount a slide hook 20 for the purpose of supporting the heddle rod 21 intermediate its ends, a portion of the rib 16 is cut away as at 22 by milling or other suitable process whereby a portion of said rod 18 is exposed to provide a portion on which may be mounted the slide hook 20, of any suitable type, such for example, as shown and described in the Kaufmann Patent No. 2,301,628, issued November 10, 1942, although any other type of slide hook, which may be adaptable, may be used at these places in the frame.

The slide hooks 20 serve to support the heddle rods 21 intermediate their ends, and the ends of the heddle rods 21 may be mounted and secured at the side strut 11 of the frame in any preferred manner. The heddles 23 are of any preferred type, preferably one of the standard forms of flat steel heddles, such as are now commonly used for weaving.

The ends of the rod 18 for supporting the slide hooks 20 may be confined within the frame by the side struts 11, although, if desired, a portion of the rib 16 may be cut away at either or both ends as indicated at 24 at the right hand end of Fig. 1, whereby the ends of the rod 18 may be sprung outward until they clear the end strut after which they may be pulled lengthwise to release the slide hooks 20 which are mounted thereon, and in this manner the heddle rods with the heddles mounted thereon may be removed from the frame.

However, other means for confining and releasing the ends of the rods 18 may be readily devised whereby the same may be easily and conveniently removed from the frame for the foregoing purpose.

In Fig. 5 of the drawing there is shown a modified form of the invention in which the main or body portion of the rail 10^a is made of wood having a metallic member 10^b secured to the inner edge thereof in a manner similar to that shown in the application for Letters Patent of John J. Kaufmann, filed August 31, 1949, Serial No. 113,429.

In the present instance the metallic member 10^b comprises a longitudinal strip having an internal groove or channel thereby providing two side walls 12^a. The inner face of each of the side walls is inclined with respect to the vertical central axis of the cross-section, whereby the groove or channel is internally tapered. The inner marginal part of the body portion 10^a of the rail is shaped complementally to the internal groove of the strip 10^b, so as to snugly fit into said groove.

The metallic member 10^b may be secured to the main or body portion 10^a of the rail in any preferred manner, as for example, by means of one of the adhesives as at 12^b which are now available for effectively securing metal to wood.

The metallic member 10^b is provided with a longitudinal rib 16^a on its inner edge portion, said rib 16^a having a rod 18^a mounted therein in the same manner as shown in the other or preferred form of the invention.

I claim:

1. A loom harness comprising top and bottom rails connected at their ends by side struts, each of said rails having a hollow metallic rib por-

tion along its inner edge extending inwardly toward the center of the frame, a metallic rod positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods.

5 2. A loom harness comprising top and bottom rails connected at their ends by side struts, each of said rails having a hollow metallic rib portion along its inner edge extending inwardly toward the center of the frame, a metallic rod 15 removably positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods.

20 3. A loom harness comprising top and bottom rails connected at their ends by side struts, each of said rails having a hollow metallic rib 25 portion along its inner edge extending inwardly toward the center of the frame, a metallic rod positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods, and a portion of the rib being recessed to permit said rod to 30 be withdrawn from the rib in which it is mounted.

35 4. A loom harness comprising top and bottom rails connected at their ends by side struts, each of said rails having a hollow metallic rib portion along its inner edge extending inwardly toward the center of the frame, a metallic rod 40 positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods, and a portion of the rib being cut away adjacent the end of the rod in which the slide hooks are 45 mounted thereby to permit said rod to be withdrawn from the rib in which it is mounted.

50 5. A loom harness comprising hollow metallic top and bottom rails connected at their ends by side struts, each of said rails having a hollow rib portion along its inner edge extending inwardly toward the center of the frame, a metallic rod positioned in the interior of said rib, portions of said rib being recessed at certain locations to expose the interiorly mounted rod 55 for portions of its length, slide hooks mounted on the exposed portions of said rods, heddle rods supported intermediate their ends by said slide hooks, and heddles mounted on said rods.

60 6. A loom harness comprising hollow metallic top and bottom rails connected at their ends by side struts, each of said rails having a hollow rib portion along its inner edge extending inwardly toward the center of the frame, a metallic rod 65 removably positioned in the interior of said rib, portions of said rib being recessed at certain locations to expose the interiorly mounted rod for portions of its length, slide hooks mounted on the exposed portions of said rods, heddle rods supported intermediate their ends by said slide 70 hooks, and heddles mounted on said rods.

75

7. A loom harness comprising hollow metallic top and bottom rails connected at their ends by side struts, each of said rails having a hollow rib portion along its inner edge extending inwardly toward the center of the frame, a metallic rod positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods, and a portion of the rib being recessed to permit said rod to be withdrawn from the rib in which it is mounted.

8. A loom harness comprising hollow metallic top and bottom rails connected at their ends by side struts, each of said rails having a hollow rib portion along its inner edge extending inwardly toward the center of the frame, a metallic rod positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods, and a portion of the rib being recessed adjacent the end of the rod on which the slide hooks are mounted thereby to permit said rod to be withdrawn from the rib in which it is mounted.

9. A loom harness comprising top and bottom rails connected at their ends by side struts, each of said rails having its main or body portion made of wood, and having a hollow metallic member mounted along its inner edge, said metallic member having a hollow rib portion extending inwardly toward the center of the frame, a metallic rod positioned in the interior of said rib, portions of said rib being recessed at certain locations to expose the interiorly mounted rod for portions of its length, slide hooks mounted on the exposed portions of said rods, heddle rods supported intermediate their ends by said slide hooks, and heddles mounted on said rods.
